CLAIM

We claim the ornamental design for a food tray, as shown and described.

DESCRIPTION

FIG. 1 is a perspective view of a food tray showing our new design;

FIG. 2 is a front elevation view thereof;

FIG. 3 is a rear elevation view thereof;

FIG. 4 is a side elevation view thereof;

FIG. 5 is a top plan view thereof;

FIG. 6 is a bottom plan view thereof; and,

FIG. 7 is an unassembled blank plan view thereof.

The dot-dash style broken lines in FIG. 7 show claimed fold lines; the lightweight dashed broken lines in FIGS. 1, 2, 3, 6, and 7 show unclaimed cutout vents and form no part of the claimed design.
